DISPLAY DEVICE

Richard Eaton Paige, Flushing, N. Y.

Application April 30, 1936, Serial No. 77,084

11 Claims. (Cl. 211—137)

This invention relates to new and useful improvements in display devices.

It is one of the objects of the invention to provide a display device which may be shipped or transported in its knock-down form with all of the several parts in flat position.

It is a further object of the invention so to construct the device that it may be readily assembled in display position without the exercise of special knowledge or skill.

It is a further object of the invention to provide a display device which is also capable of use as a support for articles to be vended.

A further object of the invention resides in a 15 construction whereby the parts will be retained in their assembled position without the aid of special fastening or securing means.

It is a further object of the invention to provide a new and improved display device which 20 may be used in more than one display position without varying the construction of any of the parts or elements thereof.

Other objects of the invention will appear as the nature of the invention is better understood, 25 and reference will be had to the following specification and claims and the accompanying drawings, in which:

Figure 1 is a perspective view of a display device constructed in accordance with one form 30 of the invention,

Figure 2 is a view in front elevation thereof on a slightly enlarged scale,

Figure 3 is a vertical sectional view thereof taken substantially on the line 3—3 of Figure 2,

Figure 4 is an enlarged detail fragmentary view 35 illustrating a portion of the means by which the members of the display device are secured together,

Figure 5 is a plan view of the blank from which 40 one of the members is formed,

Figure 6 is a plan view of the blank from which the other member is formed,

Figure 7 is a view in elevation illustrating one manner in which the display device may be used,

Figure 8 is a vertical sectional view taken substantially on the line 8—8 of Figure 7 and on an 45 enlarged scale,

Figure 9 is a perspective view illustrating a 50 slightly modified form of the invention,

Figure 10 is a top plan view of the form illustrated in Figure 9,

Figure 11 is a vertical sectional view taken substantially on the line 11—11 of Figure 9,

Figure 12 is a plan view of the blank from 55

which one of the members of the display device is formed, and;

Figure 13 is a plan view of the blank from which the other of said members of the display device is formed.

Referring again to the drawings, and particularly to Figures 1 through 6, inclusive, the display device comprises two members A and B.

When the display device is set up, as illustrated in Figure 1, the member A is adapted to assume 10 a substantially vertical position with the member B in a substantially horizontal position.

The member A may be of any desired ornamental shape and is provided with a plurality of 15 slots 15 properly positioned in its body portion for a purpose to be hereinafter described. The blank is scored along the lines 16 to provide a panel 17 which serves as a base or foot for the member A when the same is in display position. The blank is also scored along the line 18 and cut along the line 19 to provide a member 20 which 20 may be folded outwardly of the blank along the score line 18. The member B is formed from the blank shown in Figure 6, which is arcuate in form. This blank is scored along the lines 21, 22, and 23, these score lines being formed upon the outer face of the blank. The blank is further scored along the lines 24 and 25 upon the under or inner side of the blank, and all of these score 25 lines are parallel to one another and parallel with the curved edges of the blank. The curved score lines afore-mentioned divide the blank into a plurality of panels 26, 27, 28, 29, 30 and 31.

The blank from which the member B is formed is adapted to be distorted, and this operation will cause the blank to fold upon the score lines 21 to 25, inclusive, and the panels will assume the position in which they are illustrated in Figures 1 to 3, inclusive, in which position, connected panels are angularly disposed with respect to one another, which angular disposition is substantially 60° from the vertical and with those panels which are spaced with respect to one another occupying parallel planes.

In its distorted condition the member B is 45 adapted to be attached to the member A, and to accomplish this the following means is provided. The member B is provided with a plurality of tongues 35 projecting from the side edges thereof, and these tongues 35 are adapted to be received within the slots 15, heretofore mentioned, in the member A.

When the member B is distorted, tension is produced throughout its body portion, and when the tongues 35 of the member B are interengaged 50

with the slots 15 of the member A, this tension will maintain the tongues and slots in interengagement with each other to provide the connection between the members A and B. This fastening means will also maintain the member B in distorted form so long as the tongues are interengaged with the slots.

When the two parts are assembled, the member 20 is bent upwardly upon the score line 18 to a position where it will rest upon the member B at the point where the score line 21 forms the dividing line between the partitions 26 and 27, as illustrated in Figure 3.

As will be obvious from Figure 3, the device, when set up, not only produces a highly ornamental appearance, but provides a plurality of curved trough-like channels in which relatively small articles to be displayed may be placed.

When it is desired to disassemble the device, it is only necessary to disengage the tongues 35 with the slots 15, whereupon the member B may be folded to flat form upon the score lines aforementioned.

In Figures 7 and 8 I have shown a modified use of the device as illustrated in Figures 1 through 6. The device of Figures 7 and 8 is of substantially the same construction as that disclosed in Figures 1 through 6, except that the member A is of box-like form having side walls 40. In the form illustrated in Figures 7 and 8, the member B is adapted to occupy a substantially vertical plane with the member A in the horizontal plane and forming a support for the member B instead of the reverse position of the members A and B, as shown in Figures 1 through 3. While, in this form of the invention I have described the member A as being of box-like form, this is not necessary, it only being necessary to support the member A sufficiently above a support for the display device to permit of clearance of the tongues 35.

In the form of the invention illustrated in Figures 9 to 13, the vertical member is designated C, the horizontal member being designated D. The vertical member is formed from a blank of material cut along the lines 50 to remove the area designated 51. The blank is also cut along the lines 52 to permit of the removal of the area designated 53. This construction will result in two curved band-like members 56 and 57 which are adapted to be folded to a position substantially at right angles to the main body portion 58 of the member C. The member 56 is bent to the position described along two score lines 59, the member 57 being bent to the position described along the two score lines 60. The blank is also scored along a line 61 and cut along a curved line 62 to provide a member 63 which is adapted to be folded to a position at substantially right angles with the main body portion 58 along the score lines 61.

Projecting inwardly of the space resulting from the removal of the sections 51 and 53, there are tongues 65, the purpose of which will be herein-after described.

The member D is formed from an arcuate blank such as illustrated in Figure 13 and is substantially the same as the blank illustrated in Figure 6 except that in lieu of tongues 35 for engagement with slots in the member C, the blank which is designated 66 is provided with slots 67 to receive the tongues 65, heretofore mentioned. This blank 66 is scored on its outer face along the curved lines 70 and 71 and upon its inner or under face along the curved lines 72. These score lines produce panels 73, 74, 75, and 76.

When the two parts are to be assembled, the blank 66 from which the member D is formed is adapted to be distorted and folded upon the score lines 70, 71, and 72, as illustrated in Figure 11. The band-like member 56 of the member C is then bent upon the score lines 59 to form a supporting base for the member C, after which the distorted member D is passed over this base 56, and its slots 67 engage with the tongues 65 to form interlocking means for connecting the members C and D together in display position, as illustrated in Figures 9 through 11. During the setting up operation, the band-like member 57 and the member 63 are bent upwardly so that after the parts are secured together, these members being released will move to position where they will be supported by the member D to provide shelves upon which articles to be displayed may be placed. When in position to form a shelf, the member 63 will rest upon the fold line between the panels 66 and 73, the curved band-like members 57 resting upon the line of fold between the panels 75 and 76, as illustrated in Figure 11. In this form of the invention a suitable prop 80 may be employed to hold the device in display position although such prop is not necessary to the successful operation thereof.

From the foregoing it will be apparent that the present invention provides a new and improved display device which may be transported in flat position, which is readily assembled, which may be used in more than one display position, and which provides means for supporting articles to be displayed when desired.

While the invention has been herein disclosed in its preferred form it is to be understood that it is not limited to the specific constructions herein shown and that it may be practiced in other forms without departing from the spirit thereof.

Having thus described the invention, what is claimed as new, is:

1. A display device comprising two members adapted to be detachably connected together, one of said members being distorted to produce tension within the member, crease or score lines extending through the body portion of the distorted member and providing lines of fold upon which the distorted member is adapted to fold to divide the distorted member into a plurality of panels, and means for connecting said two members together and for maintaining the circumflexed member in distorted condition.

2. A display device comprising two members adapted to be detachably connected together, one of said members being of arcuate form, score or crease lines extending through the body portion of the arcuate member, said score or crease lines providing lines of fold upon which the arcuate member may be distorted to place the arcuate member under tension, and to provide a plurality of article supporting panels in the distorted arcuate member, and means for securing said members together and for maintaining the arcuate member in its distorted condition.

3. A device comprising in combination, a vertical member and a horizontal member, crease or score lines extending through the body of the horizontal member upon which said member may be distorted to produce tension therein and to provide a plurality of panels in different planes, means for securing said members together with the horizontal member in distorted form, and article supporting means overlying the panels of the horizontal member.

4. A device comprising in combination, a ver-

tical member and a horizontal member, crease or score lines extending through the body of the horizontal member upon which said member may be distorted to produce tension therein and to provide a plurality of panels in different planes, 5 means for securing said members together with the horizontal member in distorted form, and article supporting means overlying the panels of the horizontal member, said article supporting means extending from the vertical member.

10 5. A device comprising in combination, a vertical member and a horizontal member, crease or score lines extending through the body of the horizontal member upon which said member may be distorted to produce tension therein and to provide a plurality of panels in different planes, 15 means for securing said members together with the horizontal member in distorted form, and article supporting means overlying the panels 20 of the horizontal member, said article supporting means comprising integral extensions projecting from the vertical member.

15 6. A display device comprising two relatively thin flat members of bendable material, one of 25 which members is of arcuate form, a plurality of curved score or crease lines upon opposite sides of and extending throughout one dimension of said arcuate blank in parallelism with the curved edges thereof, the alternate score or crease lines 30 being formed upon the opposite faces of the blank to permit of distorting the blank to provide a plurality of adjacent connected angularly disposed panels, and means for securing said member in its distorted state to the other member.

35 7. A display device comprising two relatively thin flat members of bendable material, one of 35 which members is of arcuate form, a plurality of curved score or crease lines upon opposite sides of and extending throughout one dimension of said arcuate blank in parallelism with the curved edges thereof, the alternate score or crease lines

being formed upon the opposite faces of the blank to permit of distorting the blank to provide a plurality of adjacent angularly disposed panels, and means for detachably connecting said two members together in planes substantially at right angles to each other, and to maintain the distorted member in its circumflexed state. 5

8. A display device comprising two members secured together in angular relation, one of said members comprising a single blank of foldable material, score lines in said blank, said blank being distorted to flex upon said score lines to provide a plurality of curved angularly disposed panels extending through the distorted blank. 10

9. A display device comprising two members secured together in angular relation, one of said members comprising a single blank of foldable material, curved parallel score lines dividing said blank into curved panels or sections, said blank being distorted to flex upon said score lines 15 to throw each of the panels or sections into a 20 tangential plane.

10. A display device comprising two members secured together in angular relation, one of said members comprising a single blank of foldable 25 material, and a plurality of score lines upon each of the opposite sides of said blank, said blank being distorted to flex in opposite directions upon said score lines to provide a plurality of curved panels in spaced parallel planes and connected 30 together by panels angularly disposed with respect to said first mentioned panels. 30

11. A display device comprising two members secured together in angular relation, one of said members comprising a single flat blank of foldable material scored to provide a plurality of arcuate panels in the blank, said blank being distorted and flexed upon said score to dispose said arcuate panels in tangential planes. 35

RICHARD EATON PAIGE. 40
